UNITED STATES PATENT OFFICE

102,572

DESIGN FOR DOMESTIC WASHING MACHINE TUB

Charles E. Morgenstern, Binghamton, N. Y., as-
signor to Nineteen Hundred Corporation,
Binghamton, N. Y., a corporation of New York

Application July 16, 1935, Serial No. 57,675

Term of patent 14 years

To all whom it may concern:

Be it known that I, Charles E. Morgenstern, a citizen of the United States, residing at Binghamton, in the county of Broome and State of New York, have invented a new, original, and ornamental Design for a Domestic Washing Machine Tub, of which the following is a specification, reference being had to the accompanying drawing, forming a part thereof, in which:

Figure 1 is an elevational view of a domestic washing machine tub embodying my new design;

Figure 2 is a plan view of the tub, and

Figure 3 is a vertical sectional view through one side of the tub.

The design is characterized by a series of circumferential bands positioned outwardly from

the true cylindrical main body portion of the tub, said bands being spaced at increasingly greater distances from the bottom toward the top of said tub with the lower band being relatively close to the bottom of said tub. The design is further characterized by a sweeping, inwardly curved surface at the top commencing just above the upper band and terminating in a reversely curved, narrow neck, while a surface of sharper curvature than said top is provided at the bottom of the tub.

I claim:

The ornamental design for a domestic washing machine tub, as shown and described.

CHARLES E. MORGESTERN.
